UNITED STATES PATENT OFFICE.

GEORGE MARSH, OF LAPORTE, INDIANA.

TRACE ATTACHMENT.

1,054,432.

Specification of Letters Patent. Patented Feb. 25, 1913.

Application filed January 29, 1912. Serial No. 674,143.

To all whom it may concern:

Be it known that I, GEORGE MARSH, a citizen of the United States, residing at La-
porte, in the county of Laporte and State of
5 Indiana, have invented certain new and useful Improvements in Trace Attachments, of
which the following is a specification.

My invention relates to improvements to
trace attachments and more particularly to
10 a clip having means for engagement with the
trace and means to engage the trace chain to
support the free end thereof so that the un-
used portion of the chain will not hang
loose.

15 One of the object of my invention is to
provide a device of the character described
which may be easily shifted to different pos-
itions along the trace to support any de-
sired number of idle links.

20 Another object of my invention is to pro-
vide such a device which shall be of cheap
and simple construction, and which shall be
easy of application and efficient in opera-
tion.

25 In the drawings, Figure 1 is a plan view
showing the swingle-tree, trace, and trace
chain, with a clip device constructed accord-
ing to my invention applied thereto; Fig. 2
30 is a side elevation thereof; Fig. 3 is a sec-
tion on line 3—3 of Fig. 2; and Fig. 4 is a
perspective view of the clip.

It is obvious that various means may be
employed for supporting the idle links of
35 the tug chain, but I have found the herein-
shown construction to be cheap and efficient.
In such construction 5 indicates a part of the
swingle-tree having a trace hook 6 attached
thereto in any ordinary fashion, as by means
40 of the ring 7 secured upon the end of the
swingle-tree by staple 8.

9 indicates the trace or tug having at-
tached to the end thereof a shackle 10 to
which is secured the trace chain consisting
of a plurality of links 11—11.

45 In the use of the trace and trace chain
shown, a link 11 is engaged over the hook
6, leaving the links beyond the engaged link
hanging loose or idle so that they often
knock against the horse, besides rattling on
50 account of their vibration incident to move-
ment of the wagon on which they are used.
To obviate this I provide a clip which shall
engage the extreme link of the chain and
support it against the active portion of the

trace. Specifically when a leather tug strap 55
or trace is used with the chain, I prefer to
form the clip with a hook to engage a link
of the chain and two yieldable arms to en-
gage the leather strap. This construction
may advantageously be made of a single 60
piece of wire bent back upon itself as at 12,
to form the tongue of the hook and again
bent at 13 to form the base of the hook.
From the base the wire is bent outwardly in
opposite directions as at 14—14 for contact 65
with the outer face of the trace, and then
bent at right angles as at 15—15 for contact
with the edge of the trace, and again as at
16—16 for contact with the inner face of the
trace. For greater strength and the provi- 70
sion of greater contacting surface, the wire
may be turned back to lie parallel with the
portions 16, 15, and 14, as at 16', 15', and
14'. Preferably also, the tongue of the hook
is turned in so that the link may not acci- 75
dentially become unhooked.

In the use of the device above described it
will be apparent that the opposite trace-en-
gaging arms may be sprung apart so that
the portions 16 and 16' may be brought over 80
the edge of the trace to contact with the in-
ner surface thereof, when resiliency of the
base portions of the hook will draw them to-
gether into firm frictional engagement with
the trace portions 14—14', 15—15', 16—16' 85
and the base of the hook all contacting with
the trace. The terminal link 11 of the trace
chain may be slipped over the hook and the
clip may then be slid along the trace until
the chain is taut, when the friction between 90
the clip and the trace will maintain the
parts in their positions, so that the disad-
vantages which arise from allowing the
chain to hang loose are avoided.

The particular construction of the clip 95
may, of course, be varied to adapt it to par-
ticular trace and chain constructions.

What I claim is:—

1. A clip formed of a single piece of wire
bent to form a central link-engaging hook 100
and bent outwardly in opposite directions at
right angles to the base of said hook, thence
bent downwardly at right angles to the plane
which includes the base of the hook and
said two outwardly bent portions, and thence 105
bent inwardly parallel to said outwardly
bent portion, each said inwardly bent por-
tion being of length less than the length of

the overlying outwardly bent portion, said several bent portions constituting opposite arms for frictional and removable engagement of a trace to permit longitudinal adjustment of the clip along said trace.

2. A clip formed of a single piece of wire bent to form a central link-engaging hook and opposite arms bent for coaction respectively over the front surface, edges, and back surface of a trace, for purposes described, the wire being returned upon itself whereby said hook and two arms, constituting said wire clip, are double for presentation toward the engaged trace of wide bearing surfaces.

3. A clip formed of a single piece of wire bent to form a central link-engaging hook and bent angularly outwardly in opposite directions from the base of said hook and, 20 suitably contorted to form trace-engaging arms, the extremities of said wire being bent back into the plane of said base of the hook and said outwardly bent portion of the wire

and terminating at the angular bend between each arm and the base of the hook.

4. A clip formed of a single piece of wire bent to form a central link-engaging hook and bent outwardly in opposite directions at right angles to the base of said hook, thence bent downwardly at right angles to the plane which includes the base of the hook and said two outwardly bent portions, and thence bent inwardly parallel to said outwardly bent portion, each said inwardly bent portion being of substantially half the length of the overlying outwardly bent portion, said several bent portions constituting opposite arms for frictional and removable engagement of a trace to permit longitudinal adjustment of the clip along said trace.

In testimony whereof I hereunto set my hand in the presence of two witnesses.

GEORGE MARSH.

In the presence of—
W. LINN ALLEN,
MARY F. ALLEN.
